UNITED STATES PATENT OFFICE.

DEWIS LANDAU, OF SAN FRANCISCO, CALIFORNIA, ASSIGNOR OF ONE-FOURTH TO JOHN KUNST AND ONE-FOURTH TO EDWARD MCKENNA, OF SAN FRANCISCO, CALIFORNIA.

PIPE-COUPING.

No. 813,437.

Specification of Letters Patent.

Patented Feb. 27, 1906.

Application filed June 27, 1905. Serial No. 267,301.

To all whom it may concern:

Be it known that I, DEWIS LANDAU, a citizen of the United States, residing at San Francisco, in the county of San Francisco and State of California, have invented certain new and useful Improvements in Pipe-Couplings, of which the following is a specification.

This invention relates to improvements in pipe-couplings, the object of the invention being to provide a coupling for the ends of two pipes which will not interfere with the flow of water therethrough and in the use of which the pipes can be coupled and uncoupled very quickly.

In the accompanying drawings, Figure 1 is a front elevation of the device. Fig. 2 is a plan view thereof. Fig. 3 is a horizontal section through the two coupling-sections. Fig. 20 4 is a broken horizontal section through the handle.

Referring to the drawings, 1 2 indicate two pipes which it is desired to couple. Upon the ends of said pipes are screwed coupling-sections 3 and 4, terminating at their outer ends in opposing flanges 5 6. Within the section 4 is inserted a short tube 7, which extends into the section 3, its end abutting against an annular gasket 8, resting against a shoulder 9 in said section, and in the section 4 is also contained a spring 10, which presses against the flanged end 23 of the tube 7, so as to force the other end of said tube against the gasket 8.

Secured to the section 3 is a yoke 11, to one end of which is attached a bar 12, while at the other end is secured a tubular guide 13 for a disk or piston 14, which disk is placed around a rod 15, passing out through the guide and pivoted at its end to a lever 16, having a handle 17. A spring 18 is interposed between the flanged end of the tubular guide and the disk, so as to normally press said disk inward, and thus also press inward the pivoted end of the lever 16. Said lever has on its outer surface a groove or notch 19, which can be engaged by a tooth or hook 20 on the end of the bar 12, the upper edge of the bar behind said tooth or hook sloping upward, as shown at 21, and said lever 16 is formed in its lower edge with a recess 22,

which is semicircular in form in the upper portion, the ends of the semicircle being continued downward parallel to each other to deepen the recess. This recess is of sufficient width to pass over the coupling-section 4.

The operation of the apparatus is as follows: The two coupling-sections having been placed end to end, the lever 16 is passed over the coupling-section 4 and is moved downward until said section is in the recess 22 in said lever. The lever is then moved inward or toward the other coupling-section, so that its lower edge passes over the top of the hook or tooth 20 and behind the same, and when it has so passed the lever is pressed further down, so that said tooth or hook engages the notch or groove in the lever and secures it in place. The spring 18 permits this inward movement of the lever to be made, for it permits the outward movement of the pivotal end of the lever when sufficient pressure is applied. At the same time it normally holds the two sections of the lever together by its pressure exerted upon the piston or disk 14. Also the spring within the coupling-section 4 presses the gasket 8 against the shoulder 9 and makes a tight joint.

I claim—

1. A pipe-coupling comprising two coupling-sections adapted to be secured to the respective pipe ends, a yoke secured to one of said sections, a bar extending forward from one end of said yoke and having at its front end a hook or tooth, a device movably connected to the other end of said yoke, a spring for depressing said device toward said yoke, and a lever pivoted on said device and having a portion adapted to engage the other section, and having also a groove or notch adapted to be engaged by said tooth or hook, substantially as described.

2. A pipe-coupling comprising two coupling-sections adapted to be secured to the respective pipe ends, a yoke secured to one of said sections, a bar extending forward from one end of said yoke and having at its front end a hook or tooth, a device movably connected to the other end of said yoke, a spring for pressing said device toward said yoke, a lever pivoted on said device and having a portion adapted to engage the other section,

and having also a groove or notch adapted to be engaged by said tooth or hook, a washer in the first coupling-section, a flanged tube in the second coupling-section, its edge resting against said gasket, and a spring for pressing said flange so that the edge of the tube rests against said gasket, substantially as described.

In witness whereof I have hereunto set my hand in the presence of two subscribing witnesses.

DEWIS LANDAU.
